[57] CLAIM

The ornamental design for a high voltage fuse end fitting, substantially as shown and described.

DESCRIPTION

FIG. 1 is a perspective view of an end fitting for a high voltage fuse according to the invention;

FIG. 2 is a front elevational view of the end fitting of FIG. 1;

FIG. 3 is a side elevational view of the end fitting of FIG. 1;

FIG. 4 is a top view of the end fitting of FIG. 1; and

FIG. 5 is a bottom view of the end fitting of FIG. 1. The high voltage fuse and an exhaust control device thereon are shown in broken lines in FIG. 1 for illustrative purposes only.
